(57) **CLAIM**

We claim the ornamental design for a ring gasket, as shown and described.

DESCRIPTION

FIG. 1 is an isometric view of our design for a ring gasket; FIG. 2 is a front view of the design for the ring gasket shown in FIG. 1, the rear view being identical; and, FIG. 3 is a left side view of the design for the ring gasket shown in FIG. 1, the right side view and the top and bottom views being identical. The broken lines shown in FIGS. 1 and 2 are for illustrative purposes only and form no part of the claimed design.
